UNITED STATES PATENT OFFICE.

ERNEST J. HIFNER, OF LEXINGTON, KENTUCKY, ASSIGNOR OF ONE-TENTH TO D. W. SCOTT, OF PINE GROVE, KENTUCKY, AND THREE-FORTIETHS TO LEN SHOUSE, DR. ERNEST BRADLEY, HOGAN YANCEY, AND FRANK HAWKINS.

CARBURETER FOR INTERNAL-COMBUSTION ENGINES

1,281,778.

Specification of Letters Patent. Patented Oct. 15, 1918.

Application filed May 24, 1917. Serial No. 170,748.

To all whom it may concern:

Be it known that I, ERNEST J. HIFNER, a citizen of the United States, residing at Lexington, in the county of Fayette and State of Kentucky; have invented certain new and useful Improvements in Carbureters for Internal-Combustion Engines; and I do hereby declare the following to be a full, clear, and exact description of the invention, such as will enable others skilled in the art to which it appertains to make and use the same.

This invention relates to a new and useful carbureter for internal combustion engines and is more particularly designed for use in connection with automobile engines.

One of the objects of this invention is to provide a novel form of carbureter having operating mechanisms for opening the oil controlling valve by the suction of the engine upon the opening of the throttle valve, and to provide means for connecting the operating mechanisms with the atmosphere for venting the same and to also provide for the passage of a portion of the air therethrough for supplying air directly from the atmosphere to the fuel mixture between the throttle valve and the engine.

Another object of the invention is to provide the novel form of carbureter with an eccentrically operated plunger rod for forcing the oil controlling valve to closed position upon the closing of the throttle valve, and capable of being moved outwardly by its eccentric out of contact with the oil controlling valve simultaneously with and in accordance with the degree of opening of the throttle valve to provide for the opening of the oil controlling valve by the suction of the engine and in accordance with the limit of outward movement of the plunger rod.

Another object of this invention is to provide the novel form of carbureter with adjustable means for limiting the extreme movement of the throttle valve and the plunger rod in either of their directions.

Another object of the invention is to provide a carbureter for attaining the above objects consisting of few parts, simple in construction, efficient and durable, and which is economical to manufacture.

These and other objects and advantages will more fully appear as the nature of the

invention is more clearly understood from the following description taken in connection with the several views in the accompanying drawings, wherein I have disclosed one embodiment of the invention but which is susceptible to alterations and variations in the form, construction and arrangement of the parts to meet the exigencies of the case without departing from the spirit of the invention or the scope of the appended claims.

In the drawings,

Figure 1 is a side elevation of the carbureter.

Fig. 2 is an end view thereof.

Fig. 3 is a vertical longitudinal sectional view through the carbureter showing the interior detail construction thereof.

Referring to the drawings, wherein similar reference characters denote corresponding parts throughout the several views, 1 denotes the air intake casing or tube of the carbureter, provided with the annular flange 2 having the apertured ears 3 for securing the carbureter to the leg of the intake manifold of the engine, and adjacent the opposite end of the casing or tube 1 is provided the annular rib 4 against which is adapted to abut and be secured upon this end of the casing or tube 1 a hot air pipe leading from any suitable means for heating the air as by the exhaust manifold of the engine or the like.

Suitably journaled in the walls of the casing or tube 1 in proximity to its air intake end is the shaft 5 upon which is adjustably secured the hub 6 of the choke valve 7 by the set-screw 8, and upon the projecting end of the shaft 5 at the outer side of the casing or tube 1 is secured the rocking arm 9 provided with the sleeve 10 which is connected in any suitable manner with operating mechanisms upon the dashboard of a vehicle.

Suitably journaled in the walls of the casing or tube 1 in proximity to its connection with the leg of the intake manifold of the engine is the shaft 11 upon which is adjustably secured the hub 12 of the throttle valve 13 by the set-screw 14, and upon the end of the shaft 11 which projects outwardly through the side wall of the casing or tube 1 at the opposite side from that which the shaft 5 projects is adjustably secured one end of the rocking lever 15 having its free

end suitably secured to the throttle lever upon the steering post of the vehicle for actuating the throttle valve 13 of the casing or tube 1.

5 Upon the under side of the tube or casing 1 and substantially midway between its ends is the screw-threaded boss 16, through which is suitably threaded the oil feed tube 17 provided with the oil spray end 18. The oil tube 17 projects upwardly into the tube or casing 1 sufficiently for positioning its spray end 18 substantially centrally within the mixing chamber of the casing or tube 1 between the choke valve 7 and the throttle valve 13. The lower end of the oil tube 17 projects into the oil chamber 19 formed or secured upon the under side of the casing or tube 1 and provided with the feed pipe 20 having its lower portion formed with the 10 internal threads 21 to which is attached a supply pipe leading from any suitable oil supply reservoir, so that there is a continuous supply of oil in the oil chamber 19 and the tube 17. Also formed or secured upon the under side of the casing or tube 1 and efficiently surrounding the oil chamber 19 and its feed pipe 20 is the hot water casing or jacket 22 provided with the threaded intake boss 23 suitably connected with the upper portion of the water jacket of the engine and also provided with the threaded outlet boss 24 suitably secured to the lower portion of the water jacket of the engine, so that the oil contained in the oil chamber 19 and its 15 feed pipe 20 will be efficiently heated by the circulation of the hot water through the casing or jacket 22 from the water jacket of the engine to thereby prepare the oil within the chamber 19 for the more efficient vaporization of the oil in the mixing chamber of the casing or tube 1.

Upon the upper side of the tube or casing 1 and substantially midway between its ends is formed or secured the suction chamber 25, independent of the mixing chamber of the tube 1 between the valves 7 and 13, and within which chamber loosely operates the piston 26 adjustably threaded upon the threaded end 27 of the needle valve 28 and locked thereon through the medium of the compression washer 29 and the lock nut 30 also threaded upon the threaded end 27 of the needle valve 28 above the piston 26. The needle valve 28 is provided with the cone-shaped end 31 for opening or closing the spray end 18 of the oil feed pipe 17 upon the actuation of the piston 26 within the suction chamber 25, the cone-shaped end 31 of the needle valve being provided with an elongated stem 31' which serves as a restricting device within the oil tube 17 to prevent flooding of the carburetor and to insure the spraying of the oil should the needle valve be raised to an abnormal height through any

accidental cause. The body of the needle valve 28 is slidably mounted through the guiding member or tube 32 formed through that portion of the upper wall of the tube or casing 1 and which also provides the bottom for the suction chamber 25.

70 Connecting the upper portion of the suction chamber 25 with the end portion of the casing or tube 1 between the throttle valve 13 and the end of the tube 1, which is connected to the leg of the manifold of the engine, is the suction pipe 33, and also connecting the lower portion of the suction chamber 25 with the outside air is the air vent pipe 34 extending from a point near the bottom of the suction chamber 25 downwardly and terminating at a point slightly below the bottom of the hot water casing 22, or the air vent pipe 34 may extend farther on and terminate at any suitable and desired point.

80 The suction chamber 25 is provided with the exterior annular flange 35 provided with the oppositely disposed apertured ears 36, and upon the upper surface of the flange 35 is the gasket or packing ring 37. Upon the gasket 37 is the top 38 of the suction chamber 25, the top 38 being provided with the oppositely disposed apertured ears 39 registering with the apertured ears 36 of the flange 35 and through these apertured ears extend the threaded stems 40 of the standards 41 positioned upon the upper surface of the top 38 and are rigidly secured upon the top 38 and the top 38 is rigidly secured to the flange 35 through the medium of the nuts 42 which are screwed upon the ends of the threaded stems 40 at the under side of the ears 36 of the flange 35. Upon the upper ends of the standards 41 are the journals 43, in which is revolvably mounted the cam shaft 44 having adjustably mounted upon its projecting end the rocking arm 45 pivotally connected through the medium of the link 46 to the swinging arm 47 adjustably secured upon the projecting end of the throttle valve shaft 11 and just inwardly of the rocking arm 45. Also adjustably mounted upon the projecting end of the throttle valve shaft 11 and just inwardly of the swinging arm 47 is the check or stop member 48 provided with the upper bifurcated arm 49 having threaded therethrough the adjusting screw 50 whose lower end is adapted to contact with the stop block 51 suitably mounted upon the outer wall of the hot water casing or jacket 22. The stop member 48 is also provided with the lower arm 52 which is adapted to contact with the under side of the stop block 51 when the stop member has been swung in the opposite direction to that shown in the drawings. The upper arm 49 and the lower arm 52 of the stop member 48 are preferably disposed at substantially right angles.

to each other. The stop member 48 acting in conjunction with the stop block 51 serves to limit the swinging movements of the rocking lever 15 and consequently the movements of the throttle valve 13 and the needle valve seating plunger rod or pin 59, the latter to be hereinafter described.

Upon the cam shaft 44 is the stationary collar 53 and the adjustable collar 54 provided with the set-screw 55 for maintaining the collar 54 in its adjustments, and rigidly secured upon the shaft 44 between the collars 53 and 54 is the cam or eccentric 56 which is adapted to ride in the elongated slot 57 of the eccentric strap or head 58 of the valve seating pin 59. The valve seating plunger rod or pin 59 is slidably mounted through the externally threaded guide sleeve 60 which is adjustably threaded 20 through the threaded opening 61 formed centrally through the top 38 of the suction chamber 25, the guide sleeve 60 being maintained in adjusted position through the medium of the lock nut 62. The lower end of 25 the guide sleeve 60 is normally and suitably spaced from the lock nut 30 upon the needle valve 28 when the needle valve is in closed position, as clearly shown in Fig. 3 of the drawings. The lower end of the valve seating pin 59, however, projects beyond the lower end of the guide sleeve 60 and bears 30 against the upper end of the needle valve 28 for maintaining the needle valve in closed position when the cam 56 and the operating 35 connections of the cam shaft 44 are in the positions shown in Figs. 1 and 3 of the drawings.

The operation of the device will be briefly described as follows: Assuming the carburetor 40 to be normally inoperative, with the parts in the positions shown in the drawings, and it is desirous to start the engine, the operating mechanisms are manipulated for positioning the choke valve 7 in a desired position. The throttle valve operating mechanisms are also manipulated for positioning the throttle valve 13 to any desired degree of open position by the swinging of the rocking arm 15, shown in Fig. 1, 45 to the left. At the same time upon the opening of the throttle valve 13, the arms 45 and 47 and their connecting link 46 are simultaneously swung toward the left, thereby rotating the cam shaft 44 for causing the cam or eccentric 56 to move upwardly the valve seating pin 59 until its lower end lies substantially flush with the lower end of the guide sleeve 60 and thus relieve the 50 needle valve 28 of the force exerted thereagainst by the pin 59. The engine is now cranked or otherwise started and immediately upon suction being created within the engine cylinders, air will be drawn through the casing or tube 1 and at the same time

suction will also be created in the upper 65 portion of the suction chamber 25 through the medium of the connecting pipe which connects the upper portion of the suction chamber 25 with the tube 1 between the throttle valve 13 and the engine. This suction created in the upper portion of the suction chamber 25 will draw the piston 26 upwardly until the nut 30 contacts with the lower end of the valve seating pin 59, whereby the needle valve 28, which is operatively 70 secured to the piston 26, will be raised upwardly and the oil will be sprayed from the spray nozzle or end 18 of the oil supply tube 17 which is now free to become thoroughly intermixed with the air, preferably 75 heated air, drawn through the air intake casing or tube 1 for providing the fuel mixture which is now drawn to the engine cylinders by the suction. As long as the engine is in operation, the effect of the suction 80 through the connecting pipe 33 and the upper portion of the suction chamber 25, which is independent of the air intake casing or tube 1, the piston 26, together with the needle valve 28, are constantly maintained 85 in their upward positions against the lower end of the valve seating pin 59, whereby the oil from the chamber 19 continuously flows through the oil supply tube 17 and is sprayed into the mixing chamber of the 90 tube 1. To provide for the uninterrupted upward movement of the piston 26, the lower portion of the chamber 25 is provided with the air vent tube 34 which allows air to pass into the chamber 25 beneath the piston 100 when the piston is moved upwardly, which vent tube 24 provides for the outward flow of the air within the lower portion of the chamber 25 when the engine has been stopped by the closing of the throttle valve 105 13 and the simultaneous forcing downwardly of the valve seating pin 59 for forcing the piston 26 and the needle valve 28 downwardly for seating the valve in the spray end 18 of the oil feed tube 17.

While the piston 26 within the suction chamber 25 is of sufficient diameter that its periphery will lie in sufficient proximity to the inner surfaces of the wall of the suction chamber 25 and to be efficiently effected, actuated, and maintained in upward position by the suction of the engine, yet there is preferably provided sufficient space between the periphery of the piston 26 and the inner wall of the suction chamber 25 to prevent any possibility of the piston binding against the wall of the suction chamber which would prevent the efficient operation of the piston and the needle valve. At the same time this spacing of the piston from the wall of the suction chamber allows a small percentage of the air which has passed through the vent tube 34 into the lower por-

tion of the suction chamber 25 to pass around the periphery of the piston 26 into the upper portion of the suction chamber 25. The air is drawn through the connecting pipe 33 into the casing or tube 1 between the throttle valve 13 and the engine where this additional air becomes intermixed with the fuel mixture from the mixing chamber of the carburetor and adds materially to the efficiency of the explosive mixture which is subsequently conducted to the engine cylinders. However, the space between the piston and the wall of the suction chamber is not sufficient to interfere in any manner with the efficient operation of the piston 26 and the needle valve 28 by the suction of the engine, but, of course, when the engine is stopped, the air in the lower portion of the chamber 25 beneath the piston 26 will readily pass outwardly through the vent tube 34 for the purposes above set forth.

Having described my invention, what I claim as new and desire to secure by Letters Patent, is:—

25 1. In a carburetor of the character specified, the combination of an intake casing, a throttle valve within said intake casing, a mixing chamber within said intake casing, a tube for introducing oil into said mixing 30 chamber, a suction chamber upon said intake casing and independent thereof, a suction pipe connecting the upper portion of said suction chamber with the outlet end of said intake casing, a valve for controlling the flow 35 of oil into said mixing chamber and having its stem extending into said suction chamber, a piston upon said valve stem and loosely operating within said suction chamber and actuated by the suction of the engine created 40 above said piston for opening said oil controlling valve, an eccentrically operated plunger for releasing and for closing said oil controlling valve simultaneously with the opening and closing of said throttle valve, 45 and a vent pipe connecting the lower portion of said suction chamber with the atmosphere for supplying and for relieving air beneath said piston to provide for the free action of said piston and said oil controlling 50 valve.

2. In a carburetor of the character specified, the combination of an intake casing, a throttle valve within said intake casing, a mixing chamber within said intake casing, a tube for introducing oil into said mixing 55 chamber, a suction chamber upon said intake casing and independent thereof, a suction pipe connecting the upper portion of said suction chamber with the outlet end of 60 said intake casing, a valve for controlling the flow of oil into said mixing chamber and having its stem extending into said suction chamber, a piston upon said valve stem and loosely operating within said suction chamber and actuated by the suction of the en- 65

gine created above said piston for opening said oil controlling valve, an eccentrically operated plunger for releasing and for closing said oil controlling valve simultaneously with the opening and closing of said throttle valve, and a vent pipe connecting the lower portion of said suction chamber with the atmosphere for supplying and for relieving air beneath said piston to provide for the free action of said piston and said oil controlling valve, a portion of said air passing around said piston and through said suction pipe, whereby to supply air directly from the atmosphere to the fuel mixture between the throttle valve and the engine. 70 75 80

3. A carburetor comprising an intake casing having a throttle valve and shaft, a suction chamber upon said intake casing and independent thereof, a tube for introducing oil into said intake casing, a valve co-operating with said tube and having its stem projecting into said suction chamber, a piston upon the end of said valve stem within said suction chamber and actuated by the suction of the engine for raising said valve from 90 said tube, a removable guide sleeve adjustably secured through the top of said suction chamber, a plunger rod slidable through said guide sleeve, a head upon said plunger rod provided with an elliptical 95 opening, a shaft mounted upon the top of said suction chamber, a cam centrally mounted upon said shaft and operating within the elliptical opening of said head for raising and lowering said plunger rod, 100 and means connecting said cam shaft with the shaft of the throttle valve, whereby to operate said plunger rod to provide for the opening of said oil valve by the suction of the engine and for the closing of said oil 105 valve simultaneously with and in accordance with the degree of opening and closing of said throttle valve.

4. A carburetor comprising an intake casing having a throttle valve and shaft, a suction chamber upon said intake casing and independent thereof, a tube for introducing oil into said intake casing, a valve co-operating with said tube and having its stem projecting into said suction chamber, a piston upon the end of said valve stem within said suction chamber and actuated by the suction of the engine for raising said valve from 110 said tube, a removable guide sleeve adjustably secured through the top of said suction chamber, a plunger rod provided with an elliptical opening, a shaft mounted upon the top of said suction chamber, a cam centrally mounted upon said shaft and operating within the elliptical opening of 115 said head for raising and lowering said plunger rod, a rocker arm adjustably mounted upon the cam shaft, a rocker arm adjustably mounted upon the valve shaft, and links operatively connecting said rocker 120 125 130 135

arms, for causing the simultaneous movement of said plunger rod and said throttle valve.

5. A carbureter comprising an intake casing having a throttle valve and shaft, a suction chamber upon said intake casing and independent thereof, a tube for introducing oil into said intake casing, a valve co-operating with said tube and having its stem projecting into said suction chamber, a piston upon the end of said valve stem within said suction chamber and actuated by the suction of the engine for raising said valve from said tube, a removable guide sleeve adjustably secured through the top of said suction chamber, a plunger rod provided with an elliptical opening, a shaft mounted upon the top of said suction chamber, a cam centrally mounted upon said shaft and operating 10 within the elliptical opening of said head for raising and lowering said plunger rod,
- 15 a rocker arm adjustably mounted upon the cam shaft, a rocker arm adjustably mounted upon the valve shaft, links operatively connecting said rocker arms, for causing the simultaneous movement of said plunger rod and said throttle valve, a stop member upon said carbureter in proximity to said throttle valve shaft, and an angle member adjustably secured upon said throttle valve shaft coacting 20 with said stop member for preventing the movement of said throttle valve and said plunger rod in either direction beyond a predetermined point.

In testimony whereof I have signed my name to this specification in the presence of two subscribing witnesses.
